COSMETIC APPLICATOR

Filed Oct. 4, 1939

UNITED STATES PATENT OFFICE

2,287,321

COSMETIC APPLICATOR

Charles A. Mureau, Los Angeles, Calif.

Application October 4, 1939, Serial No. 297,821

6 Claims. (Cl. 15—137)

This invention relates to cosmetic applying devices and relates more particularly to devices for containing and applying paste lip rouge, mascara, and the like. A general object of this invention is to provide a cosmetic applicator of the character mentioned that is simple and inexpensive to manufacture and that is easy and convenient to use.

Another object of this invention is to provide a cosmetic applicator including an applying means or brush means for applying the cosmetic and a novel, effective means for delivering or ejecting the cosmetic to the brush means.

Another object of this invention is to provide a cosmetic applicator of the character mentioned in which the applying means or brush means is automatically loosened and slightly projected for easy removal when the ejecting means reaches the end of its ejection movement to indicate that the supply of cosmetic is exhausted and to facilitate the reloading of the cosmetic supply chamber to condition the device for further use.

Another object of this invention is to provide a cosmetic application of the character mentioned in which the brush means is secured to the body without the use of threads and in such a manner that it may be easily removed and reapplied.

Another object of this invention is to provide a cosmetic application of the character mentioned in which the ejecting plunger cannot be lost or disconnected and does not require removal when the cosmetic container is to be refilled.

Another object of this invention is to provide a cosmetic applicator of the character mentioned embodying a novel, compact, ejecting means having a maximum stroke so that the device may contain a large supply of cosmetic to be used for a long period before requiring refilling.

Another object of this invention is to provide a cosmetic applying device of the character mentioned embodying a brush means of novel design and construction shaped so that the cosmetic may be accurately and properly applied.

A further object of this invention is to provide a cosmetic applying device of the character mentioned that embodies a minimum number of simple, sturdy, parts.

The various objects and features of my invention will be fully understood from the following detailed description of a typical, preferred form and application of the invention, throughout which description reference is made to the accompanying drawing, in which:

Fig. 1 is a side elevation of the device of this

invention with the cap in longitudinal cross section to show the brush means. Fig. 2 is a central longitudinal detailed sectional view of the device with the cap removed showing the brush means and the ejecting means in elevation. Fig. 3 is an enlarged, longitudinal detailed sectional view of the forward portion of the device. Fig. 4 is an enlarged fragmentary longitudinal detailed sectional view of the rear portion of the device, illustrating the ejecting means. Figs. 5, 6 and 7 are enlarged transverse detailed sectional views taken as indicated by lines 5—5, 6—6, and 7—7 on Fig. 2, and Fig. 8 is a front end view with the cap and bristles removed.

10 The improved cosmetic applicator of the present invention may be said to comprise, generally, a body 10 for containing a supply of the cosmetic, applying means or brush means 11 on the body 10 and ejecting means 12 for ejecting the cosmetic from the body 10 to the brush means 11.

15 The body 10 forms a container for the supply of cosmetic and serves to support the several other parts of the device. The body 10 is an elongate tubular member and in practice may be an integral casting of a suitable material. The forward or outer end of the body 10 has a central tapered socket 13 provided with a smooth wall. An annular groove 14 of substantial depth is 20 formed in the body 10 at the inner end of the socket 13. The internal wall 15 of the body 10 adjacent and immediately inward of the groove 14 is preferably cylindrical. The main opening or cosmetic containing opening 16 of the body 10 25 extends rearwardly from the cylindrical wall 15 and in accordance with the invention is non-circular or oval in transverse cross section. The opening 16 is of substantial diameter and length to contain a considerable supply of the cosmetic. A reduced cylindrical opening 17 joins the inner end of the supply opening 16 and continues to the rear end of the body 10. A forwardly 30 facing annular shoulder 18 occurs where the opening 17 joins the oval opening 16. The extreme forward end portion 19 of the body 10 is 35 reduced in diameter to removably receive and support a cap 20. The rear portion of the body 10 through which the reduced opening 17 extends may be stepped or reduced in external 40 diameter.

45 The applying means or brush means 11 is removably secured in the forward end of the body 10 and is in communication with the opening 16 to receive the cosmetic. The brush means 11 includes a tip or brush carrier 21 provided with a 50

tapered portion 22 proportioned and finished to seat and seal in the tapered body socket 13. An annular groove 23 is formed in the carrier 21 at the inner end of its tapered portion 22 and the carrier has a cylindrical surface 24 extending rearwardly from the groove 23. The extreme inner end of the carrier 21 has a bevelled surface 25 with a substantial pitch. A shoulder 26 is formed on the carrier 21 to engage the forward end of the body 10. With the tapered portion 22 fully seated in the socket 13 the shoulder 26 engages the forward end of the body 10 to position or stop the carrier where its groove 23 registers with the groove 14 and where its surface 24 seals in the cylindrical body wall 15.

The forward portion of the carrier 21 projecting forwardly from the body 10 has two longitudinally curving and forwardly converging side surfaces 27. The other side surfaces of the projecting portion of the carrier 21 also converge forwardly but may be convex. An opening 28 extends longitudinally through the brush carrier 21. The inner portion of the opening 28 is cylindrical and of substantial diameter. The forward portion of the opening 28 is elongate in transverse cross section having two opposite side walls 29 that are substantially flat. The forward portion of the opening 28 is tapered, the walls 29 and the other wall parts of the opening converging forwardly. The walls 29 of the tapered part of the opening 28 are generally parallel with the side surfaces 27 of the carrier. The relationship between the converging part of the opening 28 and the tapered projecting portion of the carrier 21 is illustrated in Figs. 1, 2 and 5.

The brush carrier 21 is removably secured in the body 10 in such a manner that the ejecting means 12 may free it for easy removal. The means for removably securing the carrier 21 in the body 10 comprises a split spring ring 30 cooperating with the registering grooves 14 and 23. When the carrier 21 is in its normal position illustrated in the drawing the grooves 14 and 23 are in registry and the spring ring 30 is in cooperation with both grooves to dependably retain the carrier. The groove 14 is of substantial depth and is capable of entirely receiving the split spring ring 30. When the carrier 21 is to be applied to the body 10 its tapered portion 22 is inserted in the socket 13 and is moved inwardly until the bevelled surface 25 engages the spring ring 30. The engagement of the bevelled surface 25 with the spring ring 30 expands the ring and the ring is forced outwardly in the groove 14 to allow the cylindrical portion 24 of the carrier to move through the ring. When the carrier 21 reaches its final position the ring 30 snaps into the groove 23 to lock or retain the carrier in place. The spring ring 30 is constructed so that its contraction is limited and the ring remains partially engaged in the groove 14 when the carrier 21 is removed from the body 10. The walls of the groove 23 are preferably curved or convex so that an outward pressure applied to the inner end of the carrier 21 operates to expand the spring ring 30 so that the inner part of the carrier may suddenly move through the ring. It is to be understood that the spring ring 30 cooperating with the registering grooves 14 and 23 normally securely holds the carrier 21 in the position where its tapered portion 22 seats in the socket 13 and its cylindrical portion 24 seals with the cylindrical wall 15.

The applying means or brush means 11 further includes a tubular brush shank 31 arranged lon-

gitudinally in the opening 28 of the carrier 21. The rear or inner portion of the shank 31 is cylindrical and is provided with an annular flange 32 that is press fitted in the opening 28. The forward portion of the shank 31 is tapered and elongated in transverse cross section having two substantially flat sides converging forwardly in substantially parallel relation with the walls 29 of the opening 28. Because of this formation of the shank 31 the forward end of its opening 33 is restricted in capacity and is elongated in transverse cross section. The outer end of the shank 31 is substantially flush with the forward end of the carrier 21.

15 The brush means 11 further includes brush tufts or bristles 34 set in the opening 28 around the shank 31 to project from the forward end of the carrier. The group or tuft of bristles 34 completely surrounds the shank 31 and the bristles project a substantial distance from the forward extremity of the carrier 21. The bristles 34 are set in wax 35 or a mixture of wax and rosin that is unaffected by the cosmetic and that will not become brittle or flake off. It will be observed that the set portions of the bristles 34 are wedged or securely held between the tapering walls of the opening 28 and the tapered forward portion of the shank 31. The forward ends of the transversely elongated opening 28 and shank 31 shape the assembly of bristles 34 so that it too is elongate in transverse cross section. It will be observed that the oval or transversely elongated opening 33 discharges the cosmetic into the correspondingly shaped projecting portion of the bristle assembly. The flattened or oval assembly of brush tufts 34 may be employed to accurately and correctly apply the cosmetic.

20 The ejecting means 12 includes a plunger 36 operable in the cosmetic supply opening 16. The plunger 36 is secured to the forward end of a threaded stem 37. In accordance with the invention the plunger 36 is oval in end view to operate with suitable clearance in the oval opening 16. A circumferential groove is provided in the plunger 36 to carry a sealing element or packing ring 37a. The ring 37a is oval in shape to correctly seal with the wall of the oval opening 13. The plunger 36 has a forward flange or part 38 immediately in front of the packing ring 37a that serves to assist in retaining the ring in place. This part 38 is considerably smaller in diameter than the opening 16 and, therefore, may be cylindrical. The part 38 being reduced in diameter prevents the packing ring 37a from being cut or sheared off when the plunger 36 is inserted in the forward end of the body 10 when the device is assembled. When the plunger 36 is entered in the body 10 the packing ring 37a merely flexes in against the reduced part 38 and is unharmed. The reduced forward part 38 of the plunger 36 is engageable with the inner end of the brush carrier 21 when the plunger reaches the forward end of its movement and this engagement may cause the above described expansion of the spring ring 30 and a slightly forward movement of the brush carrier 21 relative to the body 10. Forward movement of the plunger 36 in the opening 16 of course forces or ejects the cosmetic from the body 10 into the assembly of bristles 34.

25 The ejecting means 12 further includes a tube 39 preferably formed of metal and extending longitudinally through the reduced body opening 17. The tube 39 is turnable in the opening 17. An enlargement or flange 40 on the tube 39 is en-

gageable with the shoulder 18 to prevent rearward movement of the tube. The forward portion 41 of the tube 39 is reduced in diameter and is internally threaded. The internal thread on the tube portion 41 mates with the thread of the stem 37. The tube 39 extends rearwardly beyond the rear end of the body 10 and is provided with a manually engageable operating part. This operating part may be in the nature of a knob or head 42 shaped to complement the rear end portion of the body 10. The head 42 has a socket 43 and the projecting rear portion of the tube 39 is roughened or knurled and force-fitted in the socket 43 to secure the head to the tube. Prior to the application of the head 42 to the tube 39 the inner end of the stem 37 is spread to prevent the stem from being entirely unthreaded from the tube 39. A tapered socket 44 may be formed in the rear end of the stem 37 to facilitate the spreading of the stem. The spread end of the stem 37 is engageable with the reduced forward portion 41 of the tube 39 to prevent unthreading or disconnection of this stem from the tube.

In the use or operation of the device the cap 20 may normally enclose the projecting bristles 34 and the projecting portion of the carrier 21. When the device is to be used the cap 20 is removed and the head 42 is turned with respect to the body 10. This produces rotation of the tube 39 relative to the stem 37. The oval plunger 36 riding in the oval opening 16 holds the stem 37 against turning relative to the body 10. Turning of the tube 39 relative to the stem 37 threads or advances the plunger 36 in the opening 16. The advancing plunger 36 forces or ejects a quantity of the cosmetic through the openings 28 and 33 into the projecting portions of the bristles 34. The cosmetic is then applied by means of the bristles 34. The projecting portion of the bristle assembly is elongate in transverse cross section or flattened so that the cosmetic may be applied with great accuracy. Following the use of the device the cap 20 is reapplied to the body 10.

After repeated use the plunger 36 approaches the forward end of its stroke and the plunger part 38 engages the inner end of the carrier 21. When this occurs the supply of the cosmetic is exhausted. By forcibly turning the head 42 with respect to the body 10 the part 38 is forcibly moved against the inner end of the carrier 21 to move the carrier forwardly. When the outward or forward force is applied to the inner end of the carrier 21 the spring ring 30 expands in the groove 14 and the cylindrical portion 24 of the carrier snaps into the ring. This frees the carrier 21 and brings the carrier to a position where its shoulder 26 is beyond the forward end of the body 10. The sudden but slight forward movement of the carrier 21 from the body 10 indicates to the user that the supply of the cosmetic is exhausted. The ring 30 remains in gripping or holding engagement with the cylindrical portion 24 to prevent unintentional displacement of the loosened carrier 21. The parts are related so that the spread end of the stem 37 at the socket 44 engages the restriction 41 to stop the forward movement of the plunger 36 so that the plunger remains in the oval opening 16 and the plunger cannot be disengaged from the opening 16. The freed or loosened carrier 21 is removed from the body 10 and the head 42 is threaded to retract the plunger 36. A replacement supply of the cosmetic is introduced into the opening 16

and the brush carrier 21 is reinserted in the forward end of the body 10 to condition the device for further use. The plunger stem 37 is received in the tube 39 which passes rearwardly from the body 10 and the stem 37 may be of substantial length so that the plunger 36 has a long stroke. The device is easy to operate and embodies a minimum number of parts.

Having described only a typical preferred form 10 and application of my invention, I do not wish to be limited or restricted to the specific details herein set forth, but wish to reserve to myself any variations or modifications that may appear to those skilled in the art, or fall within the scope 15 of the following claims:

Having described my invention, I claim:

1. A cosmetic applicator comprising a body 20 having an opening forming a reservoir for the cosmetic, cosmetic applying means removably secured to the body to have its inner face at an 25 end of the body opening and to be freed for ready removal by an outward thrust, a plunger operable in the body opening to eject the cosmetic to the applying means and engageable with the inner face of the applying means to exert an outward force thereon and thus free the applying means for removal when the supply of cosmetic is exhausted and means for operating the plunger.

30 2. A cosmetic applicator comprising a body forming a container for the cosmetic, cosmetic applying means, means securing the applying means to an end of the body releasable by an outward force on the applying means, and ejecting means 35 for ejecting the cosmetic from the body to the applying means operable to apply an outward force to the applying means to release the securing means and move the applying means outward when the supply of cosmetic in the body is exhausted, the ejecting means including a plunger 40 operable in the body and having a part engageable with the applying means, and means for moving the plunger in the body.

3. A cosmetic applicator comprising a body 45 having an opening for containing a cosmetic, cosmetic applying means comprising a carrier having a passage adapted to communicate with the body opening, and bristles on the carrier for receiving cosmetic from the passage, releasable means securing the carrier in the body opening to have the bristles project beyond the body and adapted to be released by an outward force on the carrier, a plunger operable in the body opening to eject cosmetic from the opening to the bristles and engageable with the carrier to exert an outward force on the carrier to release said releasable means when the supply of cosmetic in the opening is exhausted, and means for operating the plunger.

4. A cosmetic applicator comprising a body 60 having an opening for containing a cosmetic, there being a tapered socket in the body at the outer end of the opening, a tapered member removably fitting the socket and having a passage for conducting cosmetic from the opening, cosmetic applying means on the member receiving cosmetic from the passage, the body and member having registering grooves, a spring ring 65 cooperating with the grooves to hold the member in the socket and releasable by outward pressure on the member, a plunger in the opening, and means for operating the plunger to eject the cosmetic to the cosmetic applying means and operable to move the plunger against the member to exert an outward pressure thereon and

thus release the spring ring when the cosmetic supply in the body opening is exhausted.

5. A cosmetic applicator comprising a body having an opening for containing a cosmetic, there being a tapered socket in the body at the outer end of the opening, a tapered member removably fitting the socket and having a passage for conducting cosmetic from the opening, cosmetic applying means on the member receiving cosmetic from the passage, the body and member having registering grooves, a spring ring co-operating with the grooves to hold the member in the socket and releasable by outward pressure on the member, a bevelled surface on the inner end of the member for expanding the spring ring into the groove of the body when the member is introduced into the socket, a plunger in the opening, and means for operating the plunger to eject the cosmetic to the cosmetic applying means and operable to move the plunger against the member to exert an outward pressure thereon and thus release the spring ring when the cosmetic supply in the body opening is exhausted.

6. A cosmetic applicator comprising a body having an opening for containing a cosmetic, there being a tapered socket in the body at the outer end of the opening, a tapered member removably fitting the socket and having a passage for conducting cosmetic from the opening, cosmetic applying means on the member receiving cosmetic from the passage, the body and member having registering grooves, a spring ring co-operating with the grooves to hold the member in the socket and releasable by outward pressure on the member, the body and member having co-operating centering and sealing surfaces at opposite sides of the registering grooves, a plunger in the opening, and means for operating the plunger to eject the cosmetic to the cosmetic applying means and operable to move the plunger against the member to exert an outward pressure thereon and thus release the spring ring when the cosmetic supply in the body opening is exhausted.

CHARLES A. MUREAU.
